United States Patent Office

Des. 217,450
Patented May 5, 1970

217,450

CHAIR

Harold G. Craddock, Conover, N.C., assignor to Little
Antiques, Inc., a corporation of North Carolina

Filed Nov. 27, 1968, Ser. No. 14,710

Term of patent 14 years

Int. Cl. D6—01

U.S. Cl. D15—1

FIG. 1 is a side elevational view of a chair showing my new design;

FIG. 2 is a front elevational view thereof as viewed along reference line 2—2 on FIG. 1;

FIG. 3 is a top plan view thereof as viewed along reference line 3—3 on FIG. 1; and

FIG. 4 is a bottom plan view thereof as viewed along reference line 4—4 on FIG. 1.

I claim:

The ornamental design for a chair, as shown.
